PUMP JACK

Filed Feb. 18, 1927

UNITED STATES PATENT OFFICE

ERNEST A. MUMMIÉ, OF MINNEAPOLIS, MINNESOTA, ASSIGNOR TO MINNEAPOLIS ENGINEERING COMPANY, OF MINNEAPOLIS, MINNESOTA, A CORPORATION OF MINNESOTA

PUMP JACK

Application filed February 18, 1927. Serial No. 169,246.

My invention relates to pump jacks and has for its object to provide a jack actuated by means of a crank in which the connecting rod thereof travels substantially in a straight line in the same general direction as the pump rod.

Another object of the invention resides in providing a support and in journalling there-in a shaft for carrying said crank, said support having pivoted to it a rocking arm and in further providing a link pivoted to said crank, said connecting rod, arm and link being all pivoted together.

A still further object of the invention resides in disposing said shaft to one side of said connecting rod and positioning the pivot of said arm above said shaft so that the movement of said connecting rod is guided by said arm and is actuated by said crank through said link.

A still further object of the invention resides in positioning the pivot of said arm in such a location that the movement of the arm below the horizontal plane passing through its pivot is greater than above it so as to give a slow suction stroke and a quick return stroke to the pump rod.

A feature of the invention resides in forming said support as a case for containing driving gears for operating said shaft and in arranging on the upper portion of said case a standard to which said arm may be pivoted.

With the foregoing and other objects in view, which will appear in the following description, the invention resides in the novel combination and arrangement of parts and in the details of construction hereinafter described and claimed.

In the drawings illustrating an embodiment of my invention:

Fig. 1 is a side elevational view of a pump showing the application of my improved jack thereto.

Fig. 2 is a plan sectional view taken on line 2—2 of Fig. 1.

Fig. 3 is a longitudinal elevational view similar to Fig. 1 of a portion of the structure therein illustrated with a part of the case removed to illustrate the drive gears within the same.

In the application of pump jacks to the ordinary pumps for furnishing water for domestic and farm purposes, it is highly desirable to have the connecting rod move substantially in a straight line and in a direction corresponding with that of the pump rod and also to travel more rapidly during its return stroke than during its suction stroke. My invention accomplishes these results in a simple and expeditious manner as will become presently apparent.

For the purposes of illustrating the application of my invention, I have shown in the drawing an ordinary suction pump A which comprises a body portion 10 including a base 11 and a column 12. This column has attached to the upper portion thereof the usual pump top 13 provided with a guide bushing 14 which guides the reciprocation of a pump rod 15. The cylinder of the pump which has not been shown in the drawings, may be disposed beneath the ground at the proper elevation and serves to elevate the water in the pump body 10 where the same may be discharged through a spout 16. The usual fulcrum post and handle employed with pumps of the type illustrated may be merely disconnected when employing my jack for operating the pump, or if desired may be entirely removed from the pump structure as shown.

The jack proper comprises a case B best illustrated in Fig. 1, which is constructed of two halves 17 and 18 formed with complementary flanges 19 and 20. These case halves are bolted together by means of bolts 21 which pass through the flanges 19 and 20. When assembled the case provides a cylinder chamber which is adapted to receive a portion of the driving mechanism for the jack. Centrally located relative to the case B, are disposed two horizontal bearings 22 and 23 which journal a transversely arranged shaft 24. This shaft has keyed to it, as shown in Fig. 3, a worm wheel 25 disposed within the case B, which meshes with a corresponding worm 26 attached to a shaft 27. The shaft 27 is journaled in two bearings 28 and 127 formed on the lowermost portion of case B. Between the end of the worm 26 and bearing 127 is disposed an end thrust ball bearing 100.

32 which takes up the end thrust on shaft 27 when the jack is operating under load.

The operating parts of the jack run in oil which is insertable through an opening 33 in one of the walls of case B, normally closed by a plug 34. This oil is circulated about within the case by means of worm wheel 25 which serves to lubricate the same and worm 26, as well as the bearings 22, 23, 27 and 28. To prevent the loss of oil through the lower bearings 27 and 28, the bearing 28 is formed with a blind wall 35, while a suitable stuffing box or gland 36 is employed allowing a suitable packing 37 to be packed around the shaft 27 where the same passes outwardly through the case B.

For the purpose of driving the pump jack, a pulley 38 or any other suitable driving mechanism may be attached to the end of shaft 27. Legs 30 and 31 formed on this case serve to support the same and permit of holding the entire pump jack rigidly mounted upon the floor.

The shaft 24, as will be noted in the drawings, passes completely through the case B on both sides thereof and protrudes outwardly beyond the same a sufficient distance to permit of the attachment thereto of two cranks 39 and 40. The ends of this shaft are preferably squared as illustrated at 41 to fit corresponding holes in the cranks 39 and 40. These cranks are securely held in place upon the squared ends of said shaft by means of set screws 42 which also hold the shaft from longitudinal movement relative to the case, thereby eliminating the necessity of set screws for securing the gear 25 in position, which gear need only be keyed to the shaft as previously stated.

To the upper end of the pump rod 15 is attached a cross head 43 which may be of any desired construction and serves to pivotally support a pair of depending connecting rods 44. These connecting rods extend downwardly in proximity to the pump jack case and terminate above the shaft 24 thereof. On the upper portion of the half 18 of case B is formed a standard 45 which is provided at its upper end with a bearing 46.

An arm 49 provided with a bifurcated portion 47 at one end straddles the bearing 46. This arm is pivoted to the case by means of a pin 48 which passes through the same and is journalled in said bearing 46. The other end of arm 49 is formed with a yoke 50 adapted to straddle the column 12 of the pump A when the jack is mounted in proper relation thereto, as shown in Fig. 2. The connecting rods 44 are respectively pivoted to the end portions of the yoke 50 by bolts 51 as shown in Fig. 2. Links 52 pivoted to the cranks 39 and 40 by means of removable trunnions 55 are similarly pivoted to the ends of the yoke 50 by means of pins 53 situated in close proximity to the pivots 51 so that the

cranks 39 and 40, links 52 and arm 49 are virtually pivoted together along one axis. The cranks 39 and 40 are arranged with a number of holes 54 so that the lever arm of the same may be altered as required to vary the stroke of the pump.

In operation, the links 52 cause the connecting rods 44 to reciprocate. The arm 49 guides the movement of said rods so as to cause the said connecting rods to reciprocate in a nearly vertical direction. By disposing the bearing 46 in such a position that the arm 49 rocks to a greater degree below the horizontal plane passing through its pivot than above it, the jack can be made to operate in such a manner that the pump rod moves more slowly during its suction stroke and moves more rapidly during the return stroke, thereby utilizing to a greater degree the power available and causing the pump to operate more smoothly. This will become readily apparent when the positions of the center line of the cranks 39 and 40 indicated by the lines *a* and *b* in Fig. 1, which correspond to the extreme positions of the cross head 43 on pump rod 15 are observed. It will be noted that the angle traversed by the crank from one position to the other is greater on one side of said lines than on the other, indicating that a greater length of time is taken to cause the pump rods to move in one direction than the other. The corresponding position of the center line of the arm 49 indicated at *c* and *d* show that the same rocks to a greater extent below the horizontal plane passing through its pivot than above it. When this relationship is altered the time required for both strokes becomes more nearly equal. Disconnecting the trunnion 55 and shifting the same to any of the holes 54 in the respective cranks 39 and 40, changes the stroke of the pump rod which can be altered to meet with the requirements without affecting the operation of the jack. Under such conditions the jack operates in identically the same manner giving the slow suction stroke and the rapid return stroke.

My invention is highly meritorious in that it provides a simple and effective device for securing a slow suction stroke and a rapid return stroke to the pump rod. At the same time the jack may be disposed to the side of the pump, as becomes necessary in the installation of jacks to existing pumps and the connecting rods are caused to operate in a substantially vertical direction throughout the extent of their movement irregardless of the disposition of the jack to the side of the same. All of the operating parts of the jack are encased where the same may be properly lubricated at all times. The jack is exceedingly simple in construction and is not apt to get out of order, thereby requiring little or no attention in its operation and use.

Changes in the specific form of my invention

tion, as herein disclosed, may be made within the scope of what is claimed without departing from the spirit of my invention.

Having described my invention, what I claim as new and desire to protect by Letters Patent is:

1. A pump jack comprising a case, a shaft journalled in said case, a crank attached to said shaft, a connecting rod disposed to one side of said shaft, a link pivoted to said crank, an upstanding standard formed on said case, an arm pivoted in said standard, said connecting rod, link and arm being all connected together and transmission gearing within said case for operating said shaft.
2. A pump jack comprising a support, a shaft journalled in said support, a crank on said shaft, a connecting rod for attachment to the pump rod of a pump and disposed to one side of said shaft, a link pivoted to said crank and connected with said connecting rod, an arm pivoted to said support and connected with said connecting rod for guiding its movement, the pivot for said arm being disposed above said shaft and in substantial vertical alignment therewith.
3. A pump jack comprising a support, a shaft journalled in said support, a crank on said shaft, a connecting rod for attachment to the pump rod of a pump and disposed to one side of said shaft, a link pivoted to said crank and connected with said connecting rod, an arm pivoted to said support and connected with said connecting rod for guiding its movement, the pivot for said arm being disposed above said shaft, said arm swinging between a substantially horizontal extreme position to a downwardly inclined extreme position.
4. A pump jack comprising a case formed of halves joined in a vertical plane, a shaft journalled in said case between the halves thereof, a crank attached to said shaft, a connecting rod disposed to one side of said shaft, a link pivoted to said crank, an upstanding standard formed on one of the halves of said case lying substantially in the plane of attachment thereof, an arm pivoted to said standard, said connecting rod, link and arm being all connected together, and transmission gearing within said case for operating said shaft.

In testimony whereof, I have signed my name to this specification.

ERNEST A. MUMMIÉ.
